UNITED STATES PATENT OFFICE.

JOHN W. DARLEY, JR., OF BALTIMORE, MARYLAND, ASSIGNOR TO ERNEST J. KNABE, JR., OF BALTIMORE, MARYLAND.

AIR-DUCT AND CONNECTION FOR SELF-PLAYING GRAND PIANOS.

No. 867,114.

Specification of Letters Patent.

Patented Sept. 24, 1907.

Original application filed July 9, 1906, Serial No. 325,409. Divided and this application filed October 22, 1906.
Serial No. 340,062.

To all whom it may concern:

Be it known that I, JOHN W. DARLEY, JR., a citizen of the United States, residing at Baltimore city, and State of Maryland, have invented certain new and useful improvements in Air-Ducts and Connections for Self-Playing Grand Pianos; and I do hereby declare the following to be a full, clear, and exact description of the invention, such as will enable others skilled in the art to which it appertains to make and use the same.

My invention relates to improvements in air ducts and connections for self-playing grand pianos.

The object of my invention is to provide an air duct of such a character that the parts thereof are readily separable from each other, and which, when the parts are folded together, will form an air tight joint without the necessity of adjusting and securing the same.

With this object in view, my invention consists in the construction and combinations of parts as herein-after described and claimed.

In the accompanying drawings, Figure 1 is a sectional view of the front top portion of a grand piano, showing my invention, and Fig. 2 is a side elevation of the movable box and related parts; and Fig. 3 is a similar view with the box raised.

k represents a box in which the music rolls are placed, this box being located immediately under the folding lid of the piano. This box is provided with a cover *m*, hinged at *n*, and having a front *o* hinged to the cover *m*, so that it may be folded entirely back, and so that it may be folded partially back to form a music rest.

Within the box *k* are located the music-rolls *r* and *s*, and the tracker board *t*, connected by tubes *u* with the pneumatic portion of the apparatus. The box *k*, containing the music rolls, is only the front part of a larger box *v*, a partition *w* separating the music roll portion from the box proper. This box contains the tubes *u*, already referred to, leading to the tracker board. These tubes all run backward and pass into a header *x*, and the large box *v* is hinged at *y* to the piano case, so that the entire box *v* can fold backward about the hinge *y* when the piano lid is open, so that access may be had to the tuning pins *l* for tuning the strings. Fig. 3 represents the box *v* in the raised position.

The pneumatic tubes *u* converge together and run over a plate in the central part of the box *v*, and in the rear of this box and underneath the tubes, are the pumpers *3*. These pumpers are provided with the usual discharge openings and valves, movable covers, and suction openings and valves, which are no part of the present invention. The springs *7* attached to the

top of the box and to the pumpers normally keep the pumpers closed, and by the movement of the pedals 55 the movable members of said pumpers are lifted against the tension of said springs.

To the pumper *3* the air passes up through the passage *8* in the coupling member *9*. The air passes into the air passage *12* from the air trunk *13* through the flexible portion *18* and through a passage in the coupling member *15* to the passage *8*, the members *9* and *15* fitting against each other and having a covering 10 of leather or similar material between them to make an air tight joint. To still further insure an air tight 65 fit, I provide the means shown in the drawing, in which *14* represents a flange on the end of the trunk *13*, and *15* a movable coupling member parallel thereto and connected therewith by means of screws *16*. Springs *17* tend to press the member *15* away from the flange *14* and against the member *9*. The portion *18* of the walls of the passage *12* is made flexible, so as to permit the movement of the member *15*, so that when the box *v* is folded down into the position shown in Fig. 1, which is its normal position, a tight joint will be formed between the members *9* and *15* by means of the packing *10*. In Fig. 3 the box *v* is shown as raised, whereupon the member *15* is raised by the springs *17* until stopped by the screws *16*. I also use a similar construction to produce a tight joint between the 75 headers into which the pneumatic tubes lead from the tracker board, and from the pneumatic box. The header *x* is movably attached to the rear rail *137* of the box *v* by means of screws *138*, threaded into the rail *137* and passing loosely through holes in the header *x*, springs *139* surrounding said screws and normally keeping said header in contact with the packing *135*, which is secured on the header *136* in which are headed the pipes *170* which lead to the pneumatic box not shown. As the box *v* is raised the header *x* moves downward slightly until stopped by the heads of the screws *138*. When the box is folded down, the reverse action takes place and a tight joint is thus maintained.

Having thus described my invention, what I claim as new and desire to secure by Letters Patent of the United States, is:—

1. In a self-playing grand piano, the combination of an air duct having walls made in sections adapted to yieldingly fold against each other, and means for keeping said sections in contact with each other under spring tension, substantially as described.

2. In a self-playing grand piano, the combination of an air duct having walls made in sections, one part adapted to fold down against the other, and means for resiliently holding the ends of said sections in contact with each other, thereby making an air tight joint, when the parts are folded together, substantially as described.

3. In a self-playing grand piano, the combination of

- an air duct made in sections, members surrounding the ends of said sections where they meet, and means for folding said members together yieldingly under spring tension, substantially as described.
5. 4. In a self-playing grand piano, the combination of an air duct made in sections, members surrounding the ends of said sections where they join together, one of said members being made yielding, and springs for holding the members in air tight contact with each other, substantially as described.
5. In a self-playing grand piano, the combination of a hinged box provided with a perforated member forming an air passage, an air trunk provided with a movable member, said air trunk and member having a passage therethrough, a portion of the walls of said passage being flexible, springs for holding said movable member in contact with the member on said box, and screws for limiting the movement of said member, substantially as described.
- 10
- 15
6. In a self-playing grand piano, the combination of a hinged box adapted to carry the music rolls and tracker board, a member attached to said box and perforated to form an air passage, said member being provided with a yielding cover; an air trunk provided with a movable member, said member and air trunk having an air passage therethrough, part of the walls of said air passage being flexible, springs located between the top of said air trunk and said movable member, and screws for limiting the movement of said movable member, substantially as described. 20
- 25
- In testimony whereof, I affix my signature, in presence of two witnesses.
- JOHN W. DARLEY, JR.
